(57) **CLAIM**

The ornamental design for a spray container, as shown and described.

DESCRIPTION

FIG. 1 is a perspective view of a spray container according to the present invention.

FIG. 2 is a right side elevational view of the spray container.

FIG. 3 is a left side elevational view of the spray container.

FIG. 4 is a front elevational view of the spray container.

FIG. 5 is a rear elevational view of the spray container.

FIG. 6 is a top plan view of the spray container; and,

FIG. 7 is a bottom plan view of the spray container.

The portions shown in broken lines are solely for the purpose of illustrating context and form no part of the claimed design.
